CLAIM

The ornamental design for an expanded heart-valve stent, as shown and described.

DESCRIPTION

FIG. 1 is a perspective view of a first embodiment of an expanded heart-valve stent of the present application; FIG. 2 is a front elevational view of the first embodiment of the expanded heart-valve stent; FIG. 3 is a rear elevational view of the first embodiment of the expanded heart-valve stent; FIG. 4 is a top plan view of the first embodiment of the expanded heart-valve stent; FIG. 5 is a bottom plan view of the first embodiment of the expanded heart-valve stent; FIG. 6 is a left side elevational view of the first embodiment of the expanded heart-valve stent; FIG. 7 is a right side elevational view of the first embodiment of the expanded heart-valve stent; FIG. 8 is a perspective view of a second embodiment of an expanded heart-valve stent of the present application; FIG. 9 is a front elevational view of the second embodiment of the expanded heart-valve stent; FIG. 10 is a rear elevational view of the second embodiment of the expanded heart-valve stent; FIG. 11 is a top plan view of the second embodiment of the expanded heart-valve stent; FIG. 12 is a bottom plan view of the second embodiment of the expanded heart-valve stent; FIG. 13 is a left side elevational view of the second embodiment of the expanded heart-valve stent; FIG. 14 is a right side elevational view of the second embodiment of the expanded heart-valve stent; FIG. 15 is a perspective view of a third embodiment of an expanded heart-valve stent of the present application; FIG. 16 is a front elevational view of the third embodiment of the expanded heart-valve stent; FIG. 17 is a rear elevational view of the third embodiment of the expanded heart-valve stent; FIG. 18 is a top plan view of the third embodiment of the expanded heart-valve stent; FIG. 19 is a bottom plan view of the third embodiment of the expanded heart-valve stent; FIG. 20 is a left side elevational view of the third embodiment of the expanded heart-valve stent; FIG. 21 is a right side elevational view of the third embodiment of the expanded heart-valve stent;

FIG. 22 is a perspective view of a fourth embodiment of an expanded heart-valve stent of the present application; FIG. 23 is a front elevational view of the fourth embodiment of the expanded heart-valve stent; FIG. 24 is a rear elevational view of the fourth embodiment of the expanded heart-valve stent; FIG. 25 is a top plan view of the fourth embodiment of the expanded heart-valve stent; FIG. 26 is a bottom plan view of the fourth embodiment of the expanded heart-valve stent; FIG. 27 is a left side elevational view of the fourth embodiment of the expanded heart-valve stent; FIG. 28 is a right side elevational view of the fourth embodiment of the expanded heart-valve stent; FIG. 29 is a perspective view of a fifth embodiment of an expanded heart-valve stent of the present application; FIG. 30 is a front elevational view of the fifth embodiment of the expanded heart-valve stent; FIG. 31 is a rear elevational view of the fifth embodiment of the expanded heart-valve stent; FIG. 32 is a top plan view of the fifth embodiment of the expanded heart-valve stent; FIG. 33 is a bottom plan view of the fifth embodiment of the expanded heart-valve stent; FIG. 34 is a left side elevational view of the fifth embodiment of the expanded heart-valve stent; FIG. 35 is a right side elevational view of the fifth embodiment of the expanded heart-valve stent; FIG. 36 is a perspective view of a sixth embodiment of an expanded heart-valve stent of the present application; FIG. 37 is a front elevational view of the sixth embodiment of the expanded heart-valve stent; FIG. 38 is a rear elevational view of the sixth embodiment of the expanded heart-valve stent; FIG. 39 is a top plan view of the sixth embodiment of the expanded heart-valve stent; FIG. 40 is a bottom plan view of the sixth embodiment of the expanded heart-valve stent; FIG. 41 is a left side elevational view of the sixth embodiment of the expanded heart-valve stent; and, FIG. 42 is a right side elevational view of the sixth embodiment of the expanded heart-valve stent.
